MEANS FOR CLEANSING TUBES

Eugene A. Baerer, Ridgefield, N. J.

Application March 27, 1940, Serial No. 326,144

2 Claims. (Cl. 15—104.20)

This invention relates to means for cleansing tubes; and the invention has reference, more particularly, to novel means for cleansing and flushing the internal wall surfaces of the tubes of steam condensers and similar apparatus.

During the use and operation of condenser apparatus of the surface condenser type, wherein cold water is passed through a multiplicity of tubes into contact with the external surfaces of which is passed the steam or like vapors to be condensed, the circulated water frequently contains algae and other foreign matter which tends to deposit upon and adhere to the internal surfaces of the tubes so as, in time, to greatly diminish the heat transfer efficiency of the tubes. As a consequence of this it is necessary, in order to maintain the condenser apparatus at best working efficiency, to remove and cleanse such deposits from the internal wall surfaces of the tubes. It is therefore an object of this invention to provide novel means whereby such cleansing operations may be effected in a rapid and thorough manner, so as to quickly detach from the tube surfaces the adhering deposits and then flush the same away and out of the tube interiors.

Another object of this invention is to provide a novel tube cleansing and flushing means which comprises a cleansing water discharge head, which is carried on a supply pipe which also serves as a manipulating handle means for moving said discharge head through a tube to be cleaned, with which is combined, in advance thereof, a helical scraper brush adapted not only to exercise a scraping effect upon the tube walls but also to provide a spirally baffled cleansing water discharge passage through which water discharged from the discharge head at suitable pressure is compelled to flow against the tube walls with a swirling flushing action, to thereby quickly carry onward and out of the tube being cleaned the foreign material dislodged from the tube walls by the scraping action of the brush.

The invention has for another object to provide in the discharge head, of the above mentioned head and spiral scraping brush combination, a plurality of angularly directed cleansing water discharge vents which are disposed at a pitch more or less corresponding to the curve direction and pitch of the outgoing spiral passage formed by the helical scraper brush, whereby a spirally swirling flushing stream is projected against the tube walls and caused to flow rapidly through said outgoing passage formed by the brush.

Another object of this invention is to provide an operative coupled relation of scraping brush

and discharge head of such character that the former may be quickly detached from the latter for replacement when worn.

Other objects of this invention, not at this time more particularly enumerated, will be understood from the following detailed description of the same.

An illustrative embodiment of this invention is shown in the accompanying drawing, in which:

Fig. 1 is a fragmentary sectional view of a portion of a schematically illustrated condenser apparatus through a tube of which the novel cleansing means of this invention is operatively passed.

Fig. 2 is an enlarged side elevation of the operative end portion of the tube cleaning means of this invention; Fig. 3 is a fragmentary longitudinal sectional view thereof taken on line 3—3 in Fig. 2; and Fig. 4 is a transverse sectional view, taken on line 4—4 in Fig. 3.

Similar characters of reference are employed in the hereinabove described views, to indicate corresponding parts.

The novel tube cleaning means, in one illustrative form thereof as shown, comprises a discharge head 10 of cylindrical external shape, and of a diameter sized to permit the same to snugly fit but easily slide through the bore of a tube desired to be cleaned. Said discharge head is provided with an internal chamber 11 closed by a forward end wall 12 but open at its rearward end. Formed in the rearwardly open end of said discharge head is an internally screw threaded socket 13 into which is screwed the forward end of a rigid water supply pipe 14. This supply pipe 14 is of a length exceeding the length of the condenser tubes to be cleaned, and not only serves to supply water to the discharge head 10 for emission therefrom, but also as a handle means by which the cleansing device may be manipulated for passing the same through a tube to be cleaned and thereafter withdrawing the same therefrom. To the rearward end of said combined supply pipe and handle means 14 is connected, by any suitable form of coupling means 15, a flexible conduit 16 through which water under pressure is delivered from a suitable source of supply. Adjustably affixed upon the rearward end portion of said combined supply pipe and handle means 14 is a flanged stop collar 17, which, by abutment against

the entrance end of the tube being cleaned, suitably limits the forward operative movement of the discharge head 10, and its associated brush to be presently described, through the tube being cleaned.

5 Integrally formed in connection with the forward closed end of the discharge head 10 is an axial extension or hub 18 of substantially reduced diameter, the same being provided with an outwardly open socket 19 aligned with the longitudinal axis of the discharge head.

10 The scraper brush element of the device comprises a helical row of comparatively stiff wire bristles 20 which radiate from a twisted wire core 21 in which the same are bound, thus providing intermediate the bristle formed helices a free spiral passage. The brush thus formed is of suitable length, such length preferably being from two to four times the length of the discharge head 15 10. The butt end 22 of the wire core of said brush is inserted in the socket 19 of the extension or hub 18, and detachably affixed thereto by a set screw 23 or other suitable fastening means, thus attaching the brush in forwardly projecting and 20 axially aligned relation to the discharge head 10. The diameter of the brush thus provided is sized to be somewhat in excess of the internal diameter of a tube to be cleaned, whereby when the brush is moved through the tube bore, the extremities 25 of the bristles 20 will scrapingly engage the tube wall surfaces so as to efficiently engage and detach therefrom any deposited foreign material adherent thereto. The helical row of bristles 20 is of comparatively long pitch, and consequently 30 the outgoing spiral passage intermediate the bristle helices is sufficiently wide to provide a clearance and water flow passage of generous cross-sectional dimension.

35 Provided in the end wall 12 of the discharge head 10 to lead outwardly therethrough from the internal chamber 11 are a plurality of outwardly inclined, circumferentially spaced and angularly directed discharge vents 24. The angular disposition of said discharge vents conforms more or 40 less to the pitch angle of the spiral passage intermediate the helices of the row of brush bristles 20, so that the cleansing water discharged therefrom will be both directed against the tube wall surfaces as well as for desired swirling outflow 45 through said spiral passage of the brush.

50 In the use of the novel cleansing means, the discharge head 10 with the leading brush element is introduced into one end of the tube to be cleaned, while cleansing water, under substantial pressure (a pressure of eighty pounds more or less having been found very satisfactory) is supplied through the combined supply pipe and handle means 14. By manipulation of the supply pipe and handle means 14, the discharge head and 55 brush is advanced through the tube interior, whereby the brush bristles will scrapingly move along the tube wall surfaces so as to dislodge therefrom the deposited material adherent thereto, while the rapidly moving swirling stream of 60 cleansing water discharged from the head will flush said walls, and will catch up in its flow the dislodged material so as to carry the latter onward and thus wash the same out and away through the opposite end of the tube.

65 It will be obvious that the helical row of brush bristles provide a spiral baffle which so deflects the stream of cleansing water as to continue its

swirling flow (as indicated by arrows in Fig. 2) throughout the length of the brush, while nevertheless, since the intermediate spiral passage is uninterruptedly continuous and freely open outwardly from the brush extremity, assuring that 5 free outward flowing movement of the cleansing water stream is not impeded.

By provision of the stop collar 17 on the supply pipe and handle means 14, the movement of the head and leading brush through the tube interior 10 may be automatically arrested just before escape thereof from the opposite end of the tube, and consequently withdrawing movement of the device back through the tube, unimpeded by possible catching of the head on the tube end which 15 would be likely if the head had been permitted to be exteriorly projected therefrom, is also assured.

From the above it will be understood that a very simple, easily manipulatable and highly efficient tube cleansing means is provided. I am 20 aware that some changes could be made in the cleansing device, and therefore I do not limit my invention to the exact arrangement and construction of the devices and parts thereof as hereinabove described and as shown in the drawing, 25 said description and showing being intended to be interpreted as illustrative and not in a limiting sense.

I claim:

1. A tube cleansing means comprising, a hollow 30 discharge head, a rigid combined cleansing fluid supply pipe and handle means affixed to and communicating with said discharge head in axial rearward extension therefrom, a brush element formed by a helical row of comparatively stiff 35 wire bristles affixed to an axial core for radial extension therefrom, means to connect said brush core to said discharge head so as to dispose said brush element in axially aligned forwardly projecting extension from said discharge head, said 40 helical row of bristles defining a laterally and endwise open spiral passage about the brush axis, and said discharge head having fluid vent means at its forward end adapted to discharge cleansing fluid into and for outward flow through said 45 spiral passage.

2. A tube cleansing means comprising, a hollow discharge head, a rigid combined cleansing fluid supply pipe and handle means affixed to and communicating with said discharge head in axial 50 rearward extension therefrom, a brush element formed by a helical row of comparatively stiff wire bristles affixed to an axial core for radial extension therefrom, means to connect said brush core to said discharge head so as to dispose said 55 brush element in axially aligned forwardly projecting extension from said discharge head, said helical row of bristles defining a laterally and endwise open spiral passage about the brush axis, and said discharge head having a plurality of outwardly and laterally inclined, circumferentially spaced fluid discharge vents adapted to angularly 60 discharge cleansing fluid for outward movement through said spiral brush passage in swirling and flushing contact with the walls of a tube being 65 cleaned.

EUGENE A. BAERER.
